His Attorney.

UNITED STATES PATENT OFFICE

93,058

DESIGN FOR SHOE UPPER MATERIAL

Frederick P. Wagner, St. Louis, Mo., assignor to
Brauer Bros. Inc., St. Louis, Mo., a corpora-
tion of Missouri

Application November 2, 1932, Serial No. 45,709

Term of patent 7 years

To all whom it may concern:

Be it known that I, FREDERICK P. WAGNER, a citizen of the United States, residing in the city of St. Louis, in the State of Missouri, have invented a new, original, and ornamental Design for Shoe Upper Material of which the following is a specification, reference being had to the accompanying drawing, forming part thereof and in which

The figure shows a plan view of the surface of a section of upper material embodying the new design.

The new design consists of two identically perforated layers of shoe upper material the ap-

ertures of each of which are offset to expose areas of the inside layer, adjacent the apertures, through corresponding apertures in the outside layer, so as to render the inside layer visible at one side of the apertures but not at the opposite side thereof, and whereby to produce a shaded effect.

I claim:

The ornamental design for shoe upper material substantially as shown and described.

In testimony whereof I affix my signature this 31st day of October, 1932.

FREDERICK P. WAGNER.
